ATTY'S.

UNITED STATES PATENT OFFICE.

ALBERT WEINGAERTNER, OF ST. LOUIS, MISSOURI, ASSIGNOR TO WEINGAERTNER MANUFACTURING COMPANY, OF ST. LOUIS, MISSOURI, A CORPORATION.

SASH-BALANCE CONNECTION.

SPECIFICATION forming part of Letters Patent No. 790,412, dated May 23, 1905.

Application filed June 8, 1904. Serial No. 211,652.

To all whom it may concern:

Be it known that I, ALBERT WEINGAERTNER, a citizen of the United States, residing in the city of St. Louis and State of Missouri, have 5 invented certain new and useful Improvements in Sash-Balance Connections, of which the following is a full, clear, and exact description, reference being had to the accompanying drawings, forming part of this specification.

10 My invention relates to an improvement in the connections uniting sash-balance weights to sashes that are controlled thereby.

The invention consists in features of novelty hereinafter fully described, and pointed 15 out in the claims.

Figure I is a view showing fragments of the window-frame, a sash that operates against the frame, and my balance connection shown applied to said sash and supporting the balance-weight. Fig. II is an edge view of the 20 upper end of a sash-stile with my balance connection shown applied thereto. Fig. III is a perspective view of the sash-fixture member of my connection. Fig. IV is a perspective 25 view of the balance-weight-fixture member shown applied to the eye of the balance-weight.

1 designates an upright of a window-frame in which is mounted the pulley 2, as usual.

3 is a sash-stile that rides against the window-frame upright and is provided with a 30 pocket 4 of circular shape, as such pockets are commonly made.

5 designates a chain that travels on the pulley 2. The sash-connecting end of this chain 35 is united to the sash-stile 3 by the following means: 6 is a sash-fixture member of arch shape that fits within the pocket 4 in the sash-stile. This member 6 is provided with a longitudinal groove 7, through which the end of 40 the chain 5 is passed, as seen in Fig. I. In the arch-shaped member 6, centrally of its ends, are transverse grooves 8. These grooves receive a nail 9, that is driven into the sash-stile and extends transversely beneath the 45 member 6 to hold it in the pocket 4, the said nail being passed through the end link of the chain 5 within the slot 7, to thereby hold the chain to the sash-stile. The other end of the

chain 5 receives the attachment of the balance-weight 10, that is provided with an eye 50 11. The means of connection between the chain 5 and the balance-weight are as follows: 12 is a U-shaped loop that is provided at one end with a closed eye 13 and at its other end with an open eye 14. In connecting the balance-weight to the chain the loop 12 is first 55 passed through the eye of the balance-weight. The end of the chain 5 is then passed through the closed eye 13 of the loop, and the end link of the chain is slipped onto the open loop-eye 60 14, as seen in Fig. IV, thereby closing the space between the two loops and securely fitting the eye of the balance-weight on the loop. It will be seen that when the balance-weight hangs suspended from the loop 12 and 65 the chain to which it is connected the chain may be drawn through the closed loop-eye, thereby stretching it tight and preventing any liability of the escape of the balance-weight, in which position the chain will remain while 70 the balance-weight hangs in a suspended condition.

I claim as my invention—

1. In a sash-balance connection, the combination with a sash, of a chain, a weight connected to said chain, and means for securing said chain to said sash; said means consisting of a semicircular slotted member provided with transverse grooves, and a nail adapted to occupy said grooves and pass through the 80 chain in the slot in said member and enter said sash, substantially as set forth.

2. In a sash-balance connection, the combination with a sash, of a chain, means for connecting said chain to said sash, a balance-weight, and means for connecting said chain to said balance-weight; said last-named means consisting of a loop having a closed eye at one end and an open eye at the other end whereby said chain may be passed through said closed eye and slipped to said open eye, substantially 90 as set forth.

ALBERT WEINGAERTNER.

In presence of—

NELLIE V. ALEXANDER,
BLANCHE HOGAN.
